United States Patent

Des. 235,722
Patented July 8, 1975

235,722

PICTURE FRAME

Richard Rettick, % Creative Impressions, 914 N. Harrison
Ave., Campbell, Calif. 95008

Filed July 19, 1973, Ser. No. 380,894

Term of patent 14 years

Int. Cl. D6—07

U.S. Cl. D6—242

FIG. 2

FIG. 3

FIG. 4

FIG. 5

FIG. 6

FIG. 1 is a front and right side perspective view of a picture frame showing my new design;

FIG. 2 is a front elevational view;

FIG. 3 is a rear elevational view;

FIG. 4 is a top plan view;

FIG. 5 is a side elevational view; and

FIG. 6 is a sectional view taken along line 6-6 of FIG. 1, the cross-sections of the other three sides being the same.

I claim:

The ornamental design for a picture frame, as shown and described.
